CLAIM

The ornamental design for a dispensing container, as shown and described.

DESCRIPTION

FIG. 1 is an isometric view of a dispensing container showing my new design.

FIG. 2 is a view similar to FIG. 1 with the cover in an open position;

FIG. 3 is a top plan view;

FIG. 4 is a front elevational view;

FIG. 5 is a rear elevational view; and

FIG. 6 is a side elevational view, the opposite side being a mirror image of the side shown.

FIG. 1.

FIG. 2.

FIG. 3.

FIG. 4.

FIG. 5.

FIG. 6.
